United States Patent Office

Des. 224,656
Patented Aug. 22, 1972

224,656

TAPE DRIVE OR SIMILAR ARTICLE

Albert J. Michaud, Jr., Marlboro, and John F. Graham,
Sudbury, Mass., assignors to Honeywell, Inc., Minneapolis, Minn.

Filed Sept. 8, 1970, Ser. No. 24,888

Term of patent 14 years

Int. Cl. D14—02

U.S. Cl. D26—5

Fig. 1

Fig. 2

Fig. 3

Fig. 4

FIG. 1 is a front perspective view of a tape drive embodying our new design;

FIG. 2 is a front elevational view thereof;

FIG. 3 is a left side elevational view of the tape drive; and

FIG. 4 is a top plan view of the same.

The rear of the tape drive, not shown, is substantially plain and unornamented.

We claim:

The ornamental design for a tape drive or similar article, substantially as shown and described.
